ACTION TOY

Herman G. Fisher, East Aurora, N. Y., assignor to
Fisher-Price Toys, Inc., East Aurora, N. Y.

Application November 10, 1939, Serial No. 303,806

8 Claims. (Cl. 46—99)

This invention relates to mechanical toys and more particularly to that type in which animation is obtained by propulsion of the toy.

One of the objects of the invention is to provide an improved toy in which action of certain elements thereof is obtained by a simplified mechanism of novel form and in a manner closely simulating the natural movements and sounds of a real life counter-part.

Other objects and advantages will appear in the specification and the claims of the illustrated embodiment of the invention.

In the drawing:

Fig. 1 is a side elevational view of the toy;

Fig. 2 is a bottom plan view, and

Fig. 3 is a perspective view of the sound making element thereof.

In practicing the invention a base or frame 10 of yieldable material such as wood or the like is provided with depending side flanges 12 in which bearings 13 are secured for supporting a transverse axle 14 having wheels 15 rigidly mounted thereon. For illustrative purposes a wagon body 16 is shown mounted on the base 10.

At the forward end of the base 10 is a projecting portion 17 upon which is mounted a fanciful figure 18 having movable elements 19, shown in this embodiment of the invention as being a pair of opposed limbs of the figure 18, pivotally mounted thereon by means of pins 20. These limbs 19 are spaced away from the figure 18 by spacer elements 21 mounted upon the pins 20. A depending portion 23 of the figure 18 supports a second transverse axle 24 having wheels 25 rigidly mounted thereon.

A link 26 formed of bent wire is provided for actuating each of the movable elements 19, and the links 26 each have lower bent finger portions 27 pivotally connected with the corresponding wheel 25 by being inserted in an opening 28 in the wheel, the opening 28 being of such dimension as to receive the finger 27 therein in slip-fitting relation and being countersunk as at 29 to clear the laterally bent end portion of the finger which prevents displacement of the link 26 from the wheel 25 subsequent to assembly (Fig. 2). As illustrated, the openings 28 in the wheels 25 are eccentrically disposed with respect to the axle 24 and in diametrically opposed relation with respect to one another. The links 26 are intermediately bent as at 30 and have outwardly bent end fingers 31 which are pivotally mounted in the limbs 19 by slip-fitting insertion into appropriate openings therein at points which are spaced from the pins 20 and so located that lines

projected between corresponding points 27 and 31 are at all times offset from the line of the corresponding pin 20. The bent portion 30 prevents displacement of the fingers 31 from the limbs 19.

The axle 14 has oppositely displaced crank-like portions 32 and 33 for alternately contacting fingers 34 and 35 of a sound producing resilient striker 36 which is mounted on the underside of the base 10 by means of staples 37. The fixed end of the striker 36 has an upwardly bent portion 38 (Fig. 3) which bites into the base 10 when the staples 37 are driven into place, thus preventing accidental displacement thereof. The free end of the striker 36 has an upwardly bent portion 39 and a downwardly bent end portion forming a ridge 40 which is normally held against the base 10 by the novel shape and the inherent springiness of the striker.

In operation, as the toy is propelled along a supporting surface, the forward wheels 25 rotate and cause the links 26 to reciprocate and to swing the limbs 19 forwardly and backwardly in a manner simulating the action of a walking biped. Because of the novel relative arrangement of the wheels 25, the limbs 19, and the links 26, the limbs 19 substantially conceal the wheels 25 on the forward swing thereof. At the same time the rear wheels 15 and the axle 14 are rotating as a unit, causing the crank portions 32 and 33 to alternately contact the fingers 34 and 35 of the striker 36, thus alternately drawing the ridge 40 away from contact with the base 10 and then releasing it and allowing the striker to snap back against the base 10 with a sharp clear sound such as that made by, for this illustration, a person walking.

In the illustrated form the wheels 15 and 25 are shown as being of equal diameter. Thus, each revolution of the wheels produces two steps and two sounds; one sound to each step; and there is obtained an effect that the figure is walking through use of a minimum number of simple and rugged parts.

Although in the specification there are illustrated a pair of staples 37 for holding the striker 36 in operative position, it will be understood that a single staple or any other suitable form of connection device may be employed in lieu thereof and that such connection device will cooperate with the bent end portion 38 which cuts into the material of the base 10 to simultaneously hold the striker against the base 10 and to position it in proper parallel relation to the longitudinal axis of the toy. Also, it will be under-

stood that if the base 10 is made of pressure-resisting material such as steel or the like, a detent may be preformed in the base to receive the bent end portion 38 of the striker, within the concept of the invention. Thus, the striker is prevented from being forced away from operative contact with the crank portions 32 and 33 by the forces imposed thereon through the crank action.

It will be understood that the relative disposition of the pivot points 20 and 31 may be varied to provide any desired amplitude of reciprocatory movement of the limbs 19, and that likewise the distance between the pivot points 27 and the axis of rotation of the wheels 25 may be varied to provide any desired degree of limb movement, but that in any case the proportioning of the limbs 19 and the wheels 25 and the vertically offset relation of the axes of pivoting 20 and 24 will be so arranged that as the limbs 19 are oscillated they substantially mask the wheels 25 in side view elevation.

It will also be understood that although the invention is illustrated herein as being employed in connection with a four wheeled toy, it may be adapted with equal facility to any other desired form of toy device wherein at least one traction wheel is available to provide the motive power means for causing oscillation of a plurality of movable limb-simulating members; and also, that the motive power source may be in the form of any kind of wheel or some equivalent device in lieu of the traction wheel 25. Thus, it will be understood that the invention is particularly adapted to the provision of a life-like action toy wherein two or more limb-simulating elements are moved with a repeating action in combination with production of synchronized sound effects, such as in walking or running toys as illustrated herein, or as in a toy simulating the arm movements of a boxer, or the like.

Although only one form of the invention has been shown and described in detail, it will be apparent to those skilled in the art that the principles taught herein may be applied in various ways without departing from the spirit of the invention or the scope of the appended claims.

I claim:

1. An action toy comprising a body portion, a pair of limb-simulating elements movably mounted upon said body, means operatively connected with said limb-simulating elements for motivating the latter in opposite manner, sound producing means mounted upon said body, and means responsive to actuation of said toy and operatively associated with said sound producing means for producing multiple sound effects in timed relationship with regard to the respective movements of said limb-simulating elements, said sound producing means including a resilient striker, and said toy actuation responsive means including a rotating element having integral therewith diametrically opposed abutment portions adapted to alternately successively contact and deflect from its normal position and release the free end of said resilient striker whereby multiple sound effects are produced in response to a single rotation of said striker actuating means.

2. An action toy comprising a body portion, a pair of limb-simulating elements movably mounted upon said body, means operatively connected with said limb-simulating elements for motivating the latter in opposite manner, sound

producing means mounted upon said body, and means responsive to actuation of said toy and operatively associated with said sound producing means for producing multiple sound effects in timed relationship with regard to the respective movements of said limb-simulating elements, said sound producing means including a resilient striker having a pair of opposed extending finger portions at the free end thereof, and said toy actuation responsive means including a rotating element having diametrically opposed abutment portions adapted to alternately successively contact said extending finger portions and thereby to deflect from its normal position and release the free end of said resilient striker whereby multiple sound effects are produced in response to a single rotation of said striker actuating means.

3. A sound producing device comprising a base and a resilient striker mounted in cantilever fashion upon said base, the free end portion of said striker having a plurality of separately extending finger portions, and means for successively contacting said extending finger portions and deflecting the free end of said striker from its normal position and then releasing it.

4. A sound producing device comprising a base of yieldable material and a resilient striker mounted in cantilever fashion upon said base, the free end portion of said striker having a plurality of separately extending finger portions, and means for successively contacting said extending finger portions and deflecting the free end of said striker from its normal position and then releasing it, the anchored end portion of said striker being held in contiguous relation against said base by a connection device and having a laterally bent portion pressed into the yieldable material of said base by means of said connection device.

5. A sound producing device comprising a base and a resilient striker having an intermediately disposed portion offset in the direction of said base and a plurality of separately extending finger portions, and means for successively contacting said extending finger portions and deflecting the free end of said striker from its normal position and then releasing it.

6. A sound producing device comprising a base of yieldable material having a substantially plane surface and a striker therefor in the form of a resilient arm being mounted on said surface in cantilever fashion at one end of said striker arm by means of a connection device adapted to maintain said arm end in contiguous relation with said base, said arm end having a laterally bent portion pressed into said base yieldable material and held therein by said connection means and means exerting a twisting force upon the other end of said arm and deflecting it away from said base.

7. A sound producing device comprising a base having a detent therein and a striker in the form of a resilient arm anchored in contiguous relation with said base at one of its ends by means of a connection device, said striker arm having a laterally bent end portion inserted in said detent, the other end of said arm having a pair of projections, a shaft having a pair of angularly disposed cranks for engagement with said projections and means for rotating said shaft to intermittently actuate said arm.

8. In an action toy, a body, a wheel rotatably mounted upon said body and in contiguous relation therewith, a link operatively associated with

said wheel and having one of its ends pivotally connected thereto by means of slip-fitted engagement of a laterally bent end portion of said link in an opening formed in said wheel at a position offset from the axis of rotation thereof, said opening in said wheel being enlarged in the

region adjacent said body portion, and said laterally bent finger portion being reversely bent at its outer end in the region of said opening enlargement.

5 HERMAN G. FISHER.
